ALFRED M. LA CHAPELLE AND SAMUEL BENENSOHN, OF CHICAGO, ILLINOIS.

CARBURETER.

1,263,570.

Specification of Letters Patent. Patented Apr. 23, 1918.

Application filed April 16, 1914. Serial No. 832,266.

To all whom it may concern:

Be it known that we, ALFRED M. LA CHAPELLE and SAMUEL BENENSOHN, citizens of the United States, residing at Chicago, ⁵ county of Cook, and State of Illinois, have invented certain new and useful Improvements in Carbureters for Internal-Combustion Engines, of which the following is a full, clear, and exact specification.

10 This invention relates to improvements in carbureters more particularly adapted for use in connection with internal combustion engines and consists of the matter hereinafter described and more particularly ¹⁵ pointed out in the appended claims.

15 The object of the invention is to produce a carbureter for internal combustion engines which will, at all times, provide the proper explosive gaseous mixture for the ²⁰ engine. Another object of the invention is to so arrange the parts that a sufficient quantity of fuel is always maintained in the carbureter, said fuel being replenished or sucked into the fuel chamber of the carbureter as it is needed, by the suction of ²⁵ the engine. The carbureter includes a combined fuel and carbureting chamber to which is connected a mixing chamber, so arranged that such particles of fuel as condensed on ³⁰ the walls of the mixing chamber are delivered back into the body of fuel in the combined fuel and carbureting chamber to be again used.

These objects as well as other objects and ³⁵ advantages will appear as we proceed with our specification.

In the drawings:—

Figure 1 represents a longitudinal vertical section through a carbureter made in ⁴⁰ accordance with our invention.

Fig. 2 represents a horizontal section through the same, the plane of the section being indicated by the line 2—2 of Fig. 1.

Figs. 3, 4, 5, 6 and 7 are detail views in ⁴⁵ elevation of several of the parts used in our improved carbureter and will be more specifically referred to later.

Referring in detail to that embodiment of the invention as illustrated in the accompanying drawings: 2^a indicates the carbureter bowl which is open at its top and is there provided with interior screw threads.

The interior 2 of said bowl constitutes both a fuel chamber or reservoir adapted to contain the fuel to be carbureted and a carbureting chamber as will presently appear. Made integral with said bowl is a laterally extending hollow boss 2^b constituting an inlet valve chamber which communicates with the fuel chamber or reservoir in the ⁵⁵ carbureter bowl 2^a. Depending from the bottom wall of said boss is a tubular extension 6 in which is provided the usual fuel inlet aperture, said tubular extension of course being adapted for connection in the ⁶⁰ manner well known to the supply pipe leading from the fuel supply tank (not shown). 8 indicates the float which is adapted to control the level of the fuel in the fuel chamber or reservoir 2 of the bowl 10^a. This ⁶⁵ float is preferably made of a waterproofing cork and is of the usual horse shoe or U shape. Said float is fixed to one arm 9 of a horizontally disposed lever which is mounted on a transverse axis pin 10 having ⁷⁰ bearing in the side walls of the hollow boss 2^b. The other arm 9^a of said lever 9 has a forked end which engages an upright valve stem 5, the bottom end of which is made conical so as to close properly upon ⁷⁵ an associated seat formed in the bottom wall of the hollow boss 2^b about the top end of the fuel inlet aperture in the depending tubular extension 6. The top end of said valve stem 5 has a guiding bearing ⁸⁰ 7^a in a recess 7 of a plug 7 which has screw threaded engagement in the threaded aperture formed on the top wall of the boss 2^b. Said plug 7 may be removed when it is desired to inspect the inlet valve 5. Made ⁸⁵ integral with the bottom wall of the carbureter bowl 2^a is horizontal boss in which is provided a passageway 1. Said boss is closed at that end with the fuel chamber ⁹⁰ 2 and at its opposite end projects a short ⁹⁵ distance beyond the bowl 10 where it has threaded into it one end of a valve casing 1^a. Said casing has a rotative valve plug of well known type, which controls the admission of the air through the passage 1 in the ¹⁰⁰ horizontal boss before mentioned. Threaded to the other end of the valve casing 1^a is a tubular member which is open to the atmosphere.

11 indicates an upright spraying nozzle which is concentrically arranged with respect to the carbureter bowl. The bottom end of said spraying nozzle has a screw 5 threaded supporting engagement within an aperture formed in the top wall part of the hollow boss 1 before mentioned. In said spraying nozzle is provided a pair of upright parallel coacting passageways 11^a, and 10 11^b, respectively of approximately the same diameter.

The passageway 11^b communicates at its bottom end with the passageway formed in the boss 1. At its top, said passageway is 15 restricted in diameter for a purpose presently to appear. The bottom end of the passageway 11^a terminates short of the top of the boss 1 and is normally sealed by the fuel in the fuel chamber. The top or outlet 20 end of said passageway is likewise restricted in diameter, and extends horizontally toward the restricted outlet end of the passageway 11^b to co-act therewith. The passage 11^b constitutes the air passage for the spraying nozzle while the passage 11^a constitutes the fuel passage thereof. An adjustable means is provided in connection with the fuel passage 11^a for regulating the amount of fuel passing therethrough, said 25 means comprising a horizontally arranged spring controller valve stem 15 coaxially arranged relative to the restricted outlet of said passageway. Said valve stem is adjustable from without the carbureter bowl by means of a thumb screw 18 which is threaded through the upright walls of said bowl and a lock-nut 18^a is provided to lock said screw in the desired adjusted position.

Coaxially arranged with respect to the 30 passageway 11^b and in the bottom wall of the carbureter bowl is a threaded aperture in which is located a threaded flanged plug 3 (see Figs. 1 and 5). Said plug has a plurality of vertically arranged ports or apertures 3^a which are adapted to be closed without the carbureter bowl by a valve disk 3^c (see Figs. 1 and 4) which is held in a normally closed position against said plug 3 by means of an expansion coiled spring 3^d. 35 Said spring is mounted on a tension screw 3^e between a washer 3^e and said valve disk 3^c.

12 indicates a hollow irregularly shaped casing which is adapted to close the open 40 top of the carbureter bowl. Said casing is arranged approximately in a position inclined to the horizontal and is provided at its bottom with a threaded flange, which is adapted for engagement with the interior 45 screw threads formed at the top of said carbureter bowl. This flange also provides the top wall of the carbureter bowl and a passageway or aperture 12^a is therein provided which communicates with the interior of

said carbureter bowl and casing 12^a respectively. Said aperture is in vertical alignment with the spray nozzle 11.

In that wall of the casing which is inclined upwardly and to the left as viewed in Fig. 1, there is provided a threaded aperture adapted to receive a threaded ring 13^c (see Fig. 3). Said ring has a diametrically extending web 13^b and a tapered valve seat in that surface within the casing 12. 13 indicates a valve closure or disk (see Fig. 7) 75 which has a tapered peripheral edge adapted to close on the valve seat of said ring 13^c. Said valve disk is non-rotatively fixed to one end of the squared shank of a valve stem 13 which projects at its opposite end 80 through and beyond a squared aperture in the web 13^b of a valve ring 13 and on said stem is formed an annular shoulder 13^d adapted for engagement with the inner face of said web 13^b.

Non-rotatively mounted on said valve stem adjacent the outer surface of said web 13^d is an approximately rectangular shaped member 13^b (see Fig. 6), which has its ends so located relative to the arcuate slots 13^e in the valve closure 13 as to substantially close the same. As is apparent from an inspection of Fig. 1 of the drawings, this plate is normally located in close proximity to the outer surface of the valve closure 13 in the plane of the slots 13^e therein for a purpose soon to appear. Mounted on said stem 13^a so as to engage the outer face of the plate 13^b is a washer 13^e and adjacent the outer end of said valve stem is a similar washer 13^e and between said washers surrounding said stem is an expansion coiled spring 13^f. The outer end of said stem is screw threaded to receive a pair of nuts by means of which the desired tension of said spring may be 105 had.

The upper right hand end of said casing 12 is formed to provide a vertically arranged neck or outlet 20, the axis of which is offset from the vertical axis of the carbureter bowl so as to be approximately aligned with the axis of the fuel inlet valve 5. Said neck has laterally extending lugs by means of which the carbureter as a whole is attached to the inlet manifold of the engine. In the 115 passageway provided by said neck is located a throttle valve 19 of the well known type, which is fixed to an axis pin bearing in the wall of the neck 20. To that end of the axis pin without the neck is fixed a lever arm 22^a 120 which is connected by means of a rod 22 to a like arm fixed to the valve plug in the valve casing 1^a before mentioned. The throttle valve lever also has fixed to it a second rod or hook by means of which it may 125 be operated. Should at any time it be desired to drain such fuel as may be in fuel chamber within the carbureter bowl, a cock

4 having screw threaded engagement in an aperture in the bottom wall of the carbureter bowl is provided therefor.

The operation of our improved carbureter is as follows: and for example, we shall start with the carbureter empty and full of air at atmospheric pressure. The fuel supply tank to which the carbureter is connected is under atmospheric pressure and located in a plane below the carbureter. With these conditions prevailing the float 8 will be in its lowest position in that fuel chamber and the inlet valve 5 will be raised from its seat. The throttle valve 19 is now moved to its open position and the valve plug in the valve casing 1^a will be likewise opened as before described through the rod 22.

The engine to which the carbureter is attached is given the preliminary turn over and the suction stroke of its pistons will displace a volume of air from the interior of the casing 12 and carbureter bowl 10. A part of the primary air is admitted to the interior of the carbureter through the passageway in the boss 1, in the carbureter bowl the other part of said primary air being admitted through the valve mechanism before described in the wall of the casing 12.

The air within the carbureter is displaced more rapidly than it can enter through the passageway just mentioned, consequently a partial vacuum is established or produced in the whole interior of the carbureter, and this partial vacuum will be intensified as the engine shaft increases in speed in its preliminary "turn over".

As the air is being withdrawn from the carbureter faster than it can enter through the means before mentioned, the vacuum produced will be exerted in the next point of least resistance, this point being the supply line leading to the inlet 6. This will tend to draw or suck into the fuel chamber within the carbureter bowl, a quantity of fuel (it being borne in mind that atmospheric pressure maintains in the fuel supply tank). Fuel will thus enter the fuel chamber, and the level thereof will rise, lifting the float 5 to seat the valve plug 5 to close the entrance of additional fuel. This rising line of the fuel in the fuel chamber will, before it reaches its predetermined high level, submerge or seal the bottom end of the fuel passageway 11^a in the nozzle 11, the level rising in said passageway with the level in the fuel chamber. Such air as is now entering through the passageway in the boss 1 is the atomizing air and this air will pass up through the passage 11^b of the nozzle, and through the restriction at the top end thereof. By passing through this restricted part of said passageway, the velocity is thus increased and as said air rushes by the re-

stricted outlet end of the full passage 11^a of 65 the nozzle it will produce a higher vacuum in said passageway above the fuel level therein than is present in the fuel chamber, with the result that the column of fuel is drawn up and into the restricted end thereof 70 to pass out to be atomized and be carried upwardly by the air issuing from the passageway 11^b. The combined atomized particles of fuel and air pass upwardly from the top end of the nozzle and through the 75 aperture 12^a in the screw threaded flange of the casing 12 to mix with the primary air entering said casing through the arcuate slots 13^c in the valve disk 13 to form the proper explosive mixture. This proper mixture now passes through the conduit in the neck 20 to be delivered to the inlet manifold of the engine which directs it to the several cylinders. With the ignition system of the engine in order, the engine will now turn 85 over under its own power and the preliminary turn over is discontinued.

When the engine shaft gains in momentum the partial vacuum in the interior of the carbureter will be increased to a higher degree, and to compensate for the greater and additional amount of fuel being atomized. The valve disk 13 (which is under atmospheric pressure on that part of its face left exposed by the number 13) will move inwardly from its seat on the valve seat ring 13^c to allow of the entrance of air about its peripherical edge into the casing 12 to mix with the atomized particles of fuel therein. The air being thus admitted is the secondary 95 or auxiliary air which will reduce in richness to the proper degree the particles of atomized fuel in suspension in the mixing chamber provided for by said casing 12. The engine we will say is now running at 100 high speed and the throttle may be moved to partially restrict the passageway in the neck 20 of the casing 12 (the passage through the valve casing 1^a being simultaneously closed through the rod 22 as before 105 described) thus cutting down the supply of 110 the mixture to the engine and reducing its speed.

This speed reduction lessens the suction exerted in the carbureter by the engine and 115 the spring 13^d gradually returns the valve disk 13 to its seat on the valve ring 13^c. Such primary air as is now entering the carbureter, passes about and under the rectangular valve plate 13^b and then in through 120 the arcuate slots 13^c in the valve disk 13.

Should a "back fire" result in the inlet manifold of the engine through pre-ignition or otherwise, the pressure caused thereby in the mixing chamber, will cause the valve 125 plate 13^b on the valve stem 13^a to move outwardly against the action of the spring 13^d to allow for a direct exit of the pre-exploded

charge to pass freely through the arcuate slots 13^e in the valve disk 13 to be dissipated in the surrounding atmosphere. The spring 13^f will then return the plate 13^h to its normal position.

The relative sizes of the slots 13^e in the valve disk 13 and the aperture 12^c connecting the fuel chamber and mixing chamber is such that, said slots would offer the path 10 of least resistance to the pre-ignited gases and they will naturally pass out therethrough. This is advantageous for the reason that the fuel in the fuel chamber is not violently agitated or slashed about and 15 such fuel as does enter the mixing chamber as a liquid under these conditions are not blown out through the slots 13^e in the valve disk 13 but are again returned by gravity to the main body of fuel in the fuel chamber. 20 Such fuel as condenses on the inner faces of the wall of the casing 12 is returned by gravity back to the main body of fuel in the fuel chamber to be again used over. Should the pressure of the air in the passageway 25 provided by the boss 1 of the carbureter bowl, become greater for any reason, than that at which the best results are obtained in the spraying or atomizing nozzle, the excess air pressure in said passageway will 30 act upon the valve closure 3^e of the valve in the bottom wall of the carbureter bowl, to move the same outwardly against the action of the spring 3^d and allow such excess air to escape to the atmosphere. When 35 this excess pressure has thus been relieved, the spring will again act upon the disk 3^e to move the same to its normally closed position. It is apparent from the foregoing description that the suction produced by the 40 engine which the carbureter feeds, draws or sucks liquid fuel from the supply tank into the fuel chamber of the carbureter, the float 8 only acting to close off the inlet 6 when a predetermined high level of fuel is 45 reached in the said fuel chamber, it being immaterial whether the said fuel supply tank is located on a plane above or below the carbureter. Thus our improved carbureter eliminates the necessity of applying an air 50 pressure to the supply tank when the same is in a plane below the carbureter or providing any of the expensive "fuel feed devices" which are expensive and difficult to maintain in working order. 55 Should the supply tank be located in a plane above the carbureter, the result would be the same, as the suction on the fuel supply line to carbureter would then be assisted by the "head" of the fuel in said supply 60 tank.

Our improved carbureter is also advantageous in that the spraying nozzle is located in a plane a greater distance above the level of the fuel on the fuel chamber, than

has it been heretofore practical to make 65 them, so that the spray nozzle cannot be flooded no matter what the angular position of the carbureter may be, due to any condition.

While in describing our invention we 70 have referred to certain details of construction and specific arrangement of parts, but we do not limit ourselves thereto except as may be pointed out in the appended claims.

We claim as our invention:

75

1. A carbureter of the kind described, comprising an open top fuel bowl provided with an inlet port, said bowl being adapted to contain a body of fuel having a comparatively large surface area, a spraying device 80 located in said bowl and adapted to be supplied from the fuel therein, a float controlled valve adapted to close said inlet port when the fuel is at a predetermined level in said bowl, a casing having a contracted inlet opening attached to the open top end of said fuel bowl and adapted for connection to the engine cylinder, said casing providing a mixing chamber and said casing having side walls which are inclined upwardly and 85 outwardly from said inlet opening and having a discharge passage spaced to one side of its said inlet opening.

2. A carbureter of the kind described, comprising an open top fuel bowl provided 90 with an inlet port, said bowl being adapted to contain a body of fuel having a comparatively large surface area, a spraying device located in said bowl and adapted to be supplied from the fuel therein, a float controlled valve adapted to close said inlet port when the fuel is at a predetermined level in said bowl, a casing having a contracted 100 inlet opening attached to the open top end of said fuel bowl and adapted for connection to the engine cylinder, said casing providing a mixing chamber, said casing having side walls which are inclined upwardly and outwardly from said inlet opening and having a discharge passage spaced 105 to one side of its said inlet opening, and means providing an air inlet valve in one side wall of said casing adapted to admit an increased supply of air upon an increase in the speed of the engine above a predetermined point.

3. A carbureter of the kind described, comprising an open top fuel bowl provided with an inlet port, said bowl being adapted to contain a body of fuel having a comparatively large surface area, a spraying device located in said bowl and adapted to be supplied from the fuel therein, a float controlled valve adapted to close said inlet port when the fuel is at a predetermined 120 level in said bowl, a casing having a contracted inlet opening attached to the open top end of said fuel bowl and adapted for

110

115

120

125

connection to the engine cylinder, said casing providing a mixing chamber, said casing having side walls which are inclined upwardly and outwardly from said inlet opening and having a discharge passage spaced to one side of its said inlet opening and a duplex spring-controlled valve mechanism provided in one side wall of the said casing adapted to open to admit an increased supply of air upon the speeding up of the engine and including a member capable of

opening outwardly to exhaust the mixing chamber upon back firing of the engine.

In witness whereof, we have hereunto subscribed our names in the presence of two ¹⁵ witnesses this 13th day of April, 1914.

ALFRED M. LA CHAPELLE.
